RAILWAY CROSSING GATE

Filed July 9, 1925

2 Sheets-Sheet 2

UNITED STATES PATENT OFFICE.

RICHARD DAVIS, OF WEST SCRANTON, AND EARL GEHLING, OF SCRANTON, PENNSYLVANIA.

RAILWAY-CROSSING GATE.

Application filed July 9, 1925. Serial No. 42,521.

To all whom it may concern:

Be it known that we, RICHARD DAVIS, a citizen of the United States, residing at West Scranton, county of Lackawanna, State of Pennsylvania, and EARL GEHLING, a citizen of the United States, residing at Scranton, in the county of Lackawanna and State of Pennsylvania, have invented certain new and useful Improvements in Railway-Crossing Gates; and we do declare the following to be a full, clear, and exact description of the invention, such as will enable others skilled in the art to which it appertains to make and use the same.

Our invention relates to new and useful improvements in gates used at railway crossings and has reference more particularly to unique operating means for gates of a type having a chamber to receive fluid under pressure for closing the gate, said chamber having also an exhaust valve.

The principal object of the invention is to provide a unique arrangement of parts for simultaneously supplying air to the pressure chambers of the gates and closing the exhaust from such chambers, whereby the gates will be closed, and a further aim is to make unique provision for holding the exhaust closed until the train has passed over the crossing.

With the foregoing and minor objects in view, the invention resides in the novel subject matter hereinafter described and claimed, the description being supplemented by the accompanying drawings.

Figure 1 is a diagrammatic perspective view of the invention.

Figure 2 is an elevation partly broken away, showing two of the train-opened control valves and associated parts.

Figure 3 is a vertical sectional view through one of the valves shown in Fig. 2.

Figure 4 is a vertical sectional view showing part of the gate-actuating means.

Figure 5 is a vertical sectional view on line 5—5 of Fig. 4.

In the drawings above briefly described, R designates the rails of a railway, and H has reference to a highway crossing said railway. We have shown four gates for obstructing the highway, said gates being indicated at 1. Preferably, a hollow base 2 is provided for each of the gates 1, and the latter is secured to a horizontal rock shaft 3 passing across the upper portion of said

base, the gate being preferably weighted as at 4, to open the same after the fluid pressure which closes it, has been released. A gear 5 is secured to the shaft 3, within the base 2, said gear being in mesh with a rack 60 bar 6 on the upper end of a piston rod 7, the piston 8 of this rod being disposed in a vertical cylinder 9 within the base 2. Preferably, a bumper spring 10 is located at the upper end of the cylinder 9 to cushion the piston 8 and the gate 1, when the latter is closed. By a suitable arrangement of piping 11, the cylinders 9 of the four gates are placed in communication with each other, and the piping 11 communicates with two pipes 12 which extend in opposite directions from the railway crossing, along the railway. Four exhaust pipes 13 lead from the cylinders 9 of the gates 1 to an appropriate manifold 14, said manifold having an exhaust 15 provided with an exhaust valve 16. In the present showing, this exhaust valve is of a rotatable plug type and is provided with a spring 17 by means of which it is opened, said valve also having a crank arm 18 which is instrumental in closing it, as will be hereinafter described. Provision is made for closing this valve before pressure is admitted to the cylinders 9, so that such pressure will act to close the gates 1. Then, after the 85 train has passed, the spring 17 opens the exhaust valve 16 permitting the pressure to escape from the cylinders 9 and allowing the gates to again open. By preference, a whistle or the like 19 is disposed in one of the bases 2 and connected with the piping 11 or cylinder 9 so as to sound a warning as soon as pressure is admitted to close the gates.

At opposite sides of the highway H and spaced therefrom a suitable distance, we have shown two pressure containing pipes 20 which may communicate with any source of compressed air or other fluid under pressure. Two pipes 21 and 22 lead from each container 20 to the adjacent pipe 12, said pipes 21 and 22 being provided with normally closed control valves 23 and 24 respectively, which valves are provided with train-depressed shoes 25 and 26 by means of which they may be opened. These shoes are spaced apart any desired distances and they may be similarly spaced any adequate distance from the highway crossing.

All of the valves 23 and 24 are of the construction detailed in Fig. 3, in which

view, 27 designates a vertically disposed cylinder preferably having stuffing boxes 28 at its upper and lower ends, while the piping with which the valve is associated, connects with said casing at opposite points as shown. A vertically disposed valve plug 29 is slidably received in the casing 27 and projects through and beyond the stuffing boxes 28, the upper ends of the plugs 29 of the several valves, engaging the shoes 25 and 26, so that depression of said shoes against the action of appropriate springs 30, serves to open the valves 23 and 24. At their lower ends, the plugs 29 are pivoted to bell cranks 31 which are supported in any suitable manner, the horizontal arms of the bell cranks extending toward the highway H. Other bell cranks 32 are spaced apart along the railway track, between the valves 24, and these bell cranks have horizontal arms extending in the same directions as the corresponding arms of the cranks 31, said arms being connected to appropriate, train-depressed spring-raised shoes 33 which are disposed in any appropriate spaced relation. In spaced relation with the valve 16, we have shown a lever 34 which is fulcrumed between its ends and has one of said ends connected by a link 35 with the arm 18. Connected to the other end of this lever and to the bell cranks 31 and 32 at one side of the railway crossing, is a flexible line 36, such as a chain. A similar line 37 is connected with the bell cranks 31 and 32 at the opposite side of the crossing, and this line is attached to the arm 18 or the link 35. The bell crank 32 of the intermediate shoe 33 is preferably connected by a link 38 with the lever 34. By the construction disclosed, when a train approaches in either direction, the valves 23 and 24 will successively open and when their shoes 25 and 26 depress, said shoes rock the bell cranks 31 and pull upon the flexible line 36 or 37, thus causing the crank arm 18 to close the exhaust valve 16, while pressure is being admitted through the piping to the cylinders 9 to close the gates. When the valve 23 is opened by depression of the shoe 25, a quantity of compressed air or the like of course passes through the piping to the gates, and when the valve 24 opens, additional compressed air follows, insuring proper actuation of said gates. As the gates close, the whistle or the like 19 sounds and gives warning so that there will be no danger of injuring anyone on the highway. As the train passes over the numerous shoes, the exhaust valve 16 is held closed and when the train leaves the last shoe, said valve opens, permits escape of pressure from the cylinders 9, and the gates again open. The invention is rather simple and inexpensive, yet will be efficient and desir-

able. As excellent results may be obtained from the general construction shown, it may well be followed. However, within the scope of the invention as claimed, modifications may be made. 70

We claim:

1. In an operating means for a railway crossing gate of a type having a chamber to receive a gate-actuating fluid, and an exhaust valve for said chamber; fluid pressure supply pipes extending along the railway at opposite sides of the crossing and communicating with said chamber, normally closed control valves for said pipes remotely spaced from the crossing and having train-depressed shoes by which they are opened, other train-depressed shoes at spaced points along the track between the first named shoes, bell cranks disposed in vertical planes parallel with the rails and operatively connected with said shoes to be swung thereby about their fulcrums, the bell cranks at each side of the crossing having ends movable away from said crossing when the shoes are depressed, two flexible lines at opposite sides of the crossing connecting said ends of the bell cranks at their respective sides of said crossing, and means connecting the inner ends of said lines, said connecting means being operatively connected with said exhaust valve to close the latter when either of said valves is opened. 80

2. In an operating means for a railway crossing gate of a type having a chamber to receive a gate-actuating fluid, and an exhaust valve for said chamber; fluid pressure supply pipes extending along the railway at opposite sides of the crossing and communicating with said chamber, normally closed control valves for said pipes remotely spaced from the crossing and having train-depressed shoes by which they are opened, other train-depressed shoes at spaced points along the track between the first named shoes, bell cranks disposed in vertical planes parallel with the rails and operatively connected with said shoes to be swung thereby about their fulcrums, the bell cranks at each side of the crossing having ends movable away from said crossing when the shoes are depressed, two flexible lines at opposite sides of the crossing connecting said ends of the bell cranks at their respective sides of said crossing, and means connecting the inner ends of said lines, said connecting means being operatively connected with said exhaust valve to close the latter when either of said valves is opened. 95

3. In an operating means for a railway crossing gate of a type having a chamber to receive a gate-actuating fluid, and an exhaust valve for said chamber; fluid pressure supply pipes extending along the railway at opposite sides of the crossing and communicating with said chamber, normally closed control valves for said pipes remotely spaced from the crossing and having train-depressed shoes by which they are opened, other train-depressed shoes at spaced points along the track between the first named shoes, bell cranks disposed in vertical planes parallel with the rails and operatively connected with said shoes to be swung thereby about their fulcrums, the bell cranks at each side of the crossing having ends movable away from said crossing when the shoes are depressed, two flexible lines at opposite sides of the crossing connecting said ends of the bell cranks at their respective sides of said crossing, a lever fulcrumed between its ends adjacent the aforesaid exhaust valve, a crank arm connected to said exhaust valve to effect closing thereof, and a link connecting said crank arm to one end of said lever, the inner end of one of said flexible lines being connected to the other end of said lever, the inner end of the other line being connected to said link. 105

4. In an operating means for a railway crossing gate of a type having a chamber to receive a gate-actuating fluid, and an exhaust valve for said chamber; fluid pressure supply pipes extending along the railway at opposite sides of the crossing and communicating with said chamber, normally closed control valves for said pipes remotely spaced from the crossing and having train-depressed shoes by which they are opened, other train-depressed shoes at spaced points along the track between the first named shoes, bell cranks disposed in vertical planes parallel with the rails and operatively connected with said shoes to be swung thereby about their fulcrums, the bell cranks at each side of the crossing having ends movable away from said crossing when the shoes are depressed, two flexible lines at opposite sides of the crossing connecting said ends of the bell cranks at their respective sides of said crossing, a lever fulcrumed between its ends adjacent the aforesaid exhaust valve, a crank arm connected to said exhaust valve to effect closing thereof, and a link connecting said crank arm to one end of said lever, the inner end of one of said flexible lines being connected to the other end of said lever, the inner end of the other line being connected to said link. 110

5. In an operating means for a railway crossing gate of a type having a chamber to receive a gate-actuating fluid, and an exhaust valve for said chamber; fluid pressure supply pipes extending along the railway at opposite sides of the crossing and communicating with said chamber, normally closed control valves for said pipes remotely spaced from the crossing and having train-depressed shoes by which they are opened, other train-depressed shoes at spaced points along the track between the first named shoes, bell cranks disposed in vertical planes parallel with the rails and operatively connected with said shoes to be swung thereby about their fulcrums, the bell cranks at each side of the crossing having ends movable away from said crossing when the shoes are depressed, two flexible lines at opposite sides of the crossing connecting said ends of the bell cranks at their respective sides of said crossing, a lever fulcrumed between its ends adjacent the aforesaid exhaust valve, a crank arm connected to said exhaust valve to effect closing thereof, and a link connecting said crank arm to one end of said lever, the inner end of one of said flexible lines being connected to the other end of said lever, the inner end of the other line being connected to said link. 115

6. In an operating means for a railway crossing gate of a type having a chamber to receive a gate-actuating fluid, and an exhaust valve for said chamber; fluid pressure supply pipes extending along the railway at opposite sides of the crossing and communicating with said chamber, normally closed control valves for said pipes remotely spaced from the crossing and having train-depressed shoes by which they are opened, other train-depressed shoes at spaced points along the track between the first named shoes, bell cranks disposed in vertical planes parallel with the rails and operatively connected with said shoes to be swung thereby about their fulcrums, the bell cranks at each side of the crossing having ends movable away from said crossing when the shoes are depressed, two flexible lines at opposite sides of the crossing connecting said ends of the bell cranks at their respective sides of said crossing, a lever fulcrumed between its ends adjacent the aforesaid exhaust valve, a crank arm connected to said exhaust valve to effect closing thereof, and a link connecting said crank arm to one end of said lever, the inner end of one of said flexible lines being connected to the other end of said lever, the inner end of the other line being connected to said link. 120

7. In an operating means for a railway crossing gate of a type having a chamber to receive a gate-actuating fluid, and an exhaust valve for said chamber; fluid pressure supply pipes extending along the railway at opposite sides of the crossing and communicating with said chamber, normally closed control valves for said pipes remotely spaced from the crossing and having train-depressed shoes by which they are opened, other train-depressed shoes at spaced points along the track between the first named shoes, bell cranks disposed in vertical planes parallel with the rails and operatively connected with said shoes to be swung thereby about their fulcrums, the bell cranks at each side of the crossing having ends movable away from said crossing when the shoes are depressed, two flexible lines at opposite sides of the crossing connecting said ends of the bell cranks at their respective sides of said crossing, a lever fulcrumed between its ends adjacent the aforesaid exhaust valve, a crank arm connected to said exhaust valve to effect closing thereof, and a link connecting said crank arm to one end of said lever, the inner end of one of said flexible lines being connected to the other end of said lever, the inner end of the other line being connected to said link. 125

8. In an operating means for a railway crossing gate of a type having a chamber to receive a gate-actuating fluid, and an exhaust valve for said chamber; fluid pressure supply pipes extending along the railway at opposite sides of the crossing and communicating with said chamber, normally closed control valves for said pipes remotely spaced from the crossing and having train-depressed shoes by which they are opened, other train-depressed shoes at spaced points along the track between the first named shoes, bell cranks disposed in vertical planes parallel with the rails and operatively connected with said shoes to be swung thereby about their fulcrums, the bell cranks at each side of the crossing having ends movable away from said crossing when the shoes are depressed, two flexible lines at opposite sides of the crossing connecting said ends of the bell cranks at their respective sides of said crossing, a lever fulcrumed between its ends adjacent the aforesaid exhaust valve, a crank arm connected to said exhaust valve to effect closing thereof, and a link connecting said crank arm to one end of said lever, the inner end of one of said flexible lines being connected to the other end of said lever, the inner end of the other line being connected to said link. 130

haust valve from said chamber; a pipe leading along the track to said chamber, a container for fluid under pressure, two separate pipes leading from said fluid container to the first named pipe, normally closed control valves for said two separate pipes, train-depressed shoes for opening said valves respectively, said shoes being spaced apart along the railway, and means for closing 10 said exhaust valve when said control valves are opened.

4. In an operating means for a railway crossing gate of a type having a chamber to receive a gate-closing fluid, and an exhaust valve from said chamber; a pipe leading along the track to said chamber, a vertically

disposed valve casing from which said pipe leads, said casing being open at its upper and lower ends, a fluid supply pipe leading to said valve casing, a valve plug slidable in said casing and projecting both upwardly and downwardly therefrom, a train-depressed shoe operatively associated with the upper end of said plug for depressing and opening the latter, and means connected operatively with the lower end of said plug and said exhaust valve for closing the latter when said plug descends.

In testimony whereof we have hereunto affixed our signatures.

RICHARD DAVIS.
EARL GEHLING.
